CLAIM

The ornamental design for a flip locking lid for airtight canister, as shown and described.

DESCRIPTION

FIG. 1 is a perspective view of a flip locking lid for airtight canister showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective view of the flip locking lid for airtight canister, shown in a position of use with an exemplary canister;

FIG. 10 is another perspective view thereof, shown in a position of use with another exemplary canister.

FIG. 11 is another perspective view thereof, shown in a position of use with another exemplary canister; and,

FIG. 12 is another perspective view thereof, shown in a position of use with another exemplary canister.

The broken lines are shown for the purpose of illustrating both parts of the article as well as environmental subject matter of exemplary canisters. None of the broken lines form part of the claimed design.

1 Claim, 12 Drawing Sheets
